HEADREST HANGER

Antonio Bongiovanni, Philadelphia, Pa., assignor
of one-half to Salvatore Sgro, Philadelphia,
Pa.

Application May 29, 1935, Serial No. 24,127

2 Claims. (Cl. 155—188)

This invention relates to an improved headrest hanger for barbers' chairs and seeks, among other objects, to provide a device which may be easily and quickly attached to any conventional barber's chair for supporting the headrest of the chair when the presence of the headrest on the chair is not desired, thereby eliminating the unsanitary and inconvenient practice which is now customarily followed of laying the headrest aside.

The invention seeks, as a further object, to provide a device not only adapted to support a headrest having a flat shank but also adapted to support a headrest having a two-prong shank as well as a headrest having a single-prong shank, so that the device will thus be suited for a wide range of use.

Another object of the invention, in this connection, is to provide a device having a stop lug to coact with the flat shank of the headrest in such a way that the headrest will be prevented from tilting backwards upon the device in the way of the barber.

And the invention seeks, as a still further object, to provide a device the body of which may be stamped from sheet metal, wherein all of the incisions in the body-blank will be at one longitudinal margin thereof, to thus facilitate the stamping operation and wherein the clamp straps of the blank and the stop lug mentioned will all be bent rearwardly in the same direction.

Other and incidental objects will appear as the description proceeds and in the drawing forming a part of this application.

Figure 1 is a side elevation showing my improved device attached to a conventional barber's chair and illustrating the headrest of the chair positioned on the device.

Figure 2 is a plan view of the blank from which the device is formed.

Figure 3 is a perspective view of the device.

Figure 4 is a sectional view taken medially through the device and more clearly illustrating the manner in which the device is attached to a barber's chair.

The body of my improved headrest hanger is preferably stamped as a blank from suitable resilient sheet metal and every effort has been made to produce a blank of such construction as to reduce cost to a minimum. As particularly brought out in Figure 2, the blank is oblong in general contour and formed in one longitudinal margin of the blank are spaced parallel transverse slits 10 between which the blank is further provided with short slits 11 connected at their lower ends by a longitudinal slit 12, the

slits 11 being parallel to each other as well as parallel to the slits 10. As will be perceived, the slits 10, 11, and 12 define a header plate 13 from the lower edge of which extends straps 14 at the ends of the plate while between said straps is defined a medial tongue 15, rounded at its free end. Released by the slits 11 and 12 is an oblong stop lug 16 extending transversely throughout the major portion of the width of the tongue 15 at the root thereof. The tongue 15 is somewhat longer than the straps 14 which, as may be noted incidentally are provided with rounded outer corners, and preferably said tongue is of a width approximately three times the width of either strap which latter are of equal width. Formed in the free end portion of the tongue 15 is a pair of transversely spaced openings 17 and arranged medially with respect to said openings is a third like opening 18 disposed near the tip of the tongue.

The straps are bent rearwardly along the dotted lines shown in Figure 2 to provide a pair of U-shaped yokes 19 at the ends of the header plate 13 and the free ends of said yokes are formed with tapped openings to receive thumbscrews 20. Similarly, the lug 16 is bent rearward along the dotted line shown in Figure 2 to provide a transversely extending slot 21 at the root of the tongue 15 and, as brought out in Figure 4, the stop-lug 16 inclines downwardly and rearwardly at an obtuse angle to the header plate 13. The tongue 15 is, as also best brought out in Figure 4, curved forwardly with respect to the header plate, the free end of the tongue lying substantially at a right angle to the header plate.

Attention is now directed to the fact that the construction of the body blank is such that said blank may be stamped, at a single operation, from suitable sheet metal, all of the incisions and openings in the blank being at one longitudinal margin thereof. This feature permits the use of a correspondingly simplified die. Furthermore, as the stop lug 16 and yokes 19 are all bent in the same direction, these parts may, in the manufacture of the present device, be initially shaped, after which the tongue 15 may be curved so that a minimum number of operations will be required to produce these parts. As best seen in Figure 3, the header plate 13 is curved longitudinally.

In Figure 1 of the drawing, I have shown a conventional barber's chair including the usual pedestal 22, seat 23 having the customary depending peripheral flange 24, seat cushion 25, footrest 26, backrest 27 and headrest 28, the headrest being provided with the usual shank 29 normally

engaged with the backrest 27 and adjustable vertically thereon in the well known manner. In the present instance, I have shown a flat shank rectangular in cross section.

5 It is now to be observed that the header plate 13 of my improved headrest is curved longitudinally to conform to the curvature of the flange 24 of the seat 23 of the barber's chair while the yokes 19 are adapted to straddle said flange. Preferably, a pad 30 of rubber, fabric, or the like is adhesively secured to the rear face of the header plate 13 so as to overlie the outer face of the flange 24 and obviate abrasion thereof and, as will now be appreciated, the device may be readily 10 positioned upon the flange 24 at the rear of the barber's chair when the thumb-screws 20 may be tightened for firmly securing the device in place.

As is well known, the headrest 28 is detached from the backrest of the barber's chair whenever a barber is called upon to cut the hair of a customer and, under conventional practice, the headrest is laid aside, generally upon some convenient object. This practice is not only unsanitary but quite often, the headrest is misplaced 15 with the result that a loss of time ensues in an endeavor to locate the headrest. The present invention, therefore, is designed to overcome these difficulties. When the headrest 28 is removed from the backrest 27, the shank 29 is inserted through the slot 21, as seen in Figure 4 of the drawing, when the tongue 15 of the device will support the headrest in a conveniently accessible place but entirely out of the way of the barber. Furthermore, attention is particularly directed to 20 the fact that the stop lug 16 is inclined downwardly at the rear of the slot 21 at just the right angle to properly coat with the shank 29 for preventing the headrest from tilting rearwardly on the hanger, while also, said stop lug will provide 25 a guide for the shank when initially directed into the slot. As will be appreciated, the cushion and associated parts of the headrest provide a weight at the upper end of the shank 29 and without the stop lug 16 the headrest would tilt downwardly and rearwardly on the device, when the shank 30 would slip from the slot 21 and the headrest become displaced, particularly when the seat of the chair is revolved. By providing the stop lug 16, however, the upper end of the headrest is effectively prevented, as will be seen, from tilting 35 downwardly and rearwardly so that the possibility of accidental displacement of the headrest from the hanger is overcome.

The headrest of some barbers' chairs now in use employ a pair of spaced rod-like prongs or shanks in lieu of the shank 29 and I have accordingly provided the tongue 15 with a pair of openings 17 to removably receive said prongs so that 5 my improved device may accordingly be employed in connection with barbers' chairs equipped with headrests of the construction indicated. Furthermore, the headrests of some barbers' chairs now in use employ a single rod-like 10 prong or shank and I have accordingly provided the tongue 15 with the opening 18 to removably receive said prong. My improved hanger is thus adapted for a wide range of use.

Having thus described the invention, I claim: 15

1. A headrest hanger including a header plate provided at its rear side with means for attachment to a barber's chair and having a depending tongue projecting forwardly from the lower edge of the plate, said tongue being provided with a 20 slot therein to receive the shank of a headrest, and a stop lug extending rearwardly of the plate from the lower edge thereof at said slot to coat with said shank for limiting the headrest against 25 tilting movement.

2. A headrest hanger formed from a sheet metal body-blank having its upper longitudinal margin providing a header plate and having its lower longitudinal margin formed with a pair of spaced transverse slits defining companion straps 30 at the ends of the blank separated by an intervening tongue and said blank being further provided at the base of said tongue between said first-mentioned slits with a pair of spaced transverse slits connected at their lower ends by a longi- 35 tudinal slit in the blank to provide a stop lug, said straps being bent laterally and upwardly at one side of the header plate to provide yokes at the rear of said plate and said tongue being bent laterally in a direction opposite to said yokes to 40 extend forwardly at the front side of the plate, and clamping elements carried by said yokes for connecting the header plate with a barber's chair, said stop lug being bent rearwardly with respect to the header plate to provide a slot in said tongue 45 adapted to receive the shank of a headrest and said lug being disposed to engage said shank for limiting the headrest against forward tilting movement.

ANTONIO BONGIOVANNI. 50
